UNITED STATES PATENT OFFICE.

HORACE R. ALLEN, OF INDIANAPOLIS, INDIANA.

MOWING-MACHINE.

SPECIFICATION forming part of Letters Patent No. 291,020, dated January 1, 1884.

Application filed December 1, 1882. (No model.)

To all whom it may concern:

Be it known that I, HORACE R. ALLEN, of the city of Indianapolis, county of Marion, and State of Indiana, have invented certain new and useful Improvements in Mowing-Machines, of which the following is a specification.

Referring to the accompanying drawings, which are made a part hereof, and on which 10 similar letters of reference indicate similar parts, Figure 1 is a front elevation (showing some parts in cross-section) of a machine embodying my invention, as seen from the dotted line $z z$ in Figs. 2 and 3; Fig. 2, a top or plan view of the same; Fig. 3, a longitudinal vertical sectional view, as seen when looking to the right from the dotted line $y y$ in Figs. 1 and 2; Fig. 4, a view of the opposite side of the shoe P and casting Q to that shown in Fig. 20 3 when in the relation they occupy while being put together; Fig. 5, a sectional view, on an enlarged scale, looking downwardly from the dotted line $x x$ in Fig. 3; Fig. 6, a sectional view looking to the left from the dotted line $w w$ in Fig. 5; Fig. 7, a sectional view of the clutch on the dotted line $v v$ in Fig. 2; Fig. 8, a cross-section of the cutter-bar and finger-bar on the dotted line $u u$; Fig. 9, a cross-section of the finger-bar alone on the 25 dotted line $t t$; Fig. 10, an inside view of the hub of the wheel A, as seen from the dotted line $y y$ in Fig. 1; Fig. 11, a cross-section of the same on the dotted line $r r$; Fig. 12, a detail sectional view similar to a portion of Fig. 3; and Fig. 13, a view similar to Fig. 12, except that the point at which the section is taken is nearer the outer end of the portion P'.

In said drawings, the portions marked A A' represent the wheels of the machine; B, 40 the axle; C, the frame-work or inclosing-casing, usually termed the "gear-case;" D, the tongue or pole; E, the seat; F G H I J K, a system of gear-wheels; L, a clutch for throwing said wheels into or out of action; M, a 45 shaft running from the gear-case to the cutter-bar; N, said cutter-bar; O, the finger-bar; P, the shoe; Q, a hollow casting connecting the gear-case C and said shoe; R, a brace-rod for holding said casting and the shoe in place; S, 50 a combined brace for the tongue D and support for the cutter-bar lifter, and T said cutter-bar lifter.

The wheels A A' are in general form not unlike other wheels for the purpose. Two of the spokes a in each wheel, however, instead of 55 entering the hub straight, as spokes usually do, turn at right angles at their inner ends, as shown, and are thus adapted to serve as pivots for the pawls a' , which engage with the ratchet-wheels A^2 , and thus form the usual ratchet-connection between the hub and the axle. Wires a^2 serve both as pins to hold said pawls upon 60 their pivots, and as springs to keep them engaged with the ratchet-wheels.

The axle B is similar to other axles for like 65 purposes, and is provided with the various bearings, splines, &c., which are necessary to accommodate the parts mounted thereon. A bearing, B', near one end serves as a point of attachment for the braces R and S. Said bearing is secured in place by collars $b' b'$.

The gear-case C serves to inclose the system 70 of driving-gears and to support the shaft M and the upper end of the casting Q. Its form is clearly shown in the drawings.

The tongue D is secured to the axle B at its rear end and to the brace S at a point in front of said axle, and serves the usual purpose of a tongue. The seat E is secured thereto in the ordinary manner.

In the system of gears shown that marked 75 F is internally toothed, and is fixedly secured inside the casing C. Those marked G and H are mounted by means of short pivot-shafts g and h upon the loosely-mounted wheel I upon 80 the axle, and mesh into both the internal gear, F, and the smaller or pinion portion of the double gear J. The larger or bevel portion of said wheel J meshes into the pinion K on the shaft M. When the clutch L is not engaged with the hub of the wheel I, the gears remain motionless, and the shaft M and cutting machinery are therefore out of operation. When, however, the clutch L is thrown into engagement with the hub of the wheel I, said 85 wheel is thereby put in motion, and with it the wheels G and H, which, through the engagement of said wheels G and H with the internal gear, F, also drive the wheel J. This arrangement gives said wheel J a rapid rate of speed, 90 and thus also drives the wheel K and shaft M very fast, as is necessary in mechanism for this purpose.

The clutch by which the gearing is thrown

into or out of operation is, owing to the construction of the machine, necessarily a revolving clutch, and is therefore of somewhat peculiar construction. It is composed of the 5 clutch portion L, which is mounted on the axle B, and is caused to revolve therewith by means of a spline, b, and the operating portion L', which is permitted to partially rotate on the axle. A pin, l', passes down through the 10 spline and the axle, and serves to hold the same. The operating portion L' has inclined faces, (see particularly Fig. 2,) which come in contact with the pin l'. As said portion L' is moved around past this pin, it is forced back, 15 and thus draws the clutch part L out of engagement with the clutch part formed by the hub of the wheel I, which permits the gears and cutting mechanism to be idle. Small notches at the termination of the inclined faces 20 receive the pin, and thus hold the clutch disengaged until purposely released. As soon as the part L' is released, which is done by turning it slightly, it is operated to force the clutch back into engagement by the spring L', which 25 is placed between it and the hub t of one portion of the cutter-bar lifter; or, in case no cutter-bar lifter of this kind is used, a simple collar is used instead of the hub, as shown in Fig. 7. This clutch has been described at 30 length because it is desirable in order that the operation of the machine may be fully understood. Said clutch is not, however, claimed herein, but is reserved as the subject-matter of a future application for Letters Patent.

35 The shaft M extends from above the gear-case, where it bears the fly-wheel M', to the cutter-bar, where it bears the crank M''. It rests in bearings on the gear-case, as shown, and is driven by the system of gears just described. The fly-wheel M' is a feature of my 40 invention. It is mounted loosely on the shaft M, and thus said shaft is permitted to revolve without necessarily driving said fly-wheel, except when engaged by means of a ratchet or 45 clutch device. Such a device is shown so arranged that when the shaft is put in motion in its usual direction it actuates the fly-wheel only by the friction existing between the fixed hub m on the shaft and the hub m' of said fly-wheel. As will be readily understood, this 50 permits the shaft to start much more easily than if the fly-wheel were rigid therewith, as the force required to put a heavy body suddenly in motion is considerable. The friction between the parts soon puts the fly-wheel in 55 motion, and after a few revolutions the motion is the same as if it were rigid with the shaft. The ratchet being of such form that the fly-wheel cannot turn faster than the shaft, 60 it will be readily seen that in case the shaft is held back from any cause—as the choking of the knives in the grass or grain—the fly-wheel will operate to drive said shaft forward as efficiently as though it were rigid therewith. 65 Those familiar with the art will readily understand that, owing to the frequent stopping and starting of the rapidly-revolving shaft M,

a rigid fly-wheel would be impracticable, as the severe jerks caused by starting the same suddenly would be very liable to break portions of the mechanism, besides making the labor of starting the machine very heavy. My invention obviates these disadvantages, 70 and at the same time secures in a mowing-machine the well-known advantages arising from the use of a fly-wheel in machinery where "dead-centers" are to be overcome or un- 75 equal resistance compensated for.

The cutter-bar N and finger-bar O, as shown, 80 are of a desirable form. These parts, however, being substantially like those shown and described in another application for Letters Patent, will not be further described herein.

The shoe P is similar in its general form to the ordinary shoe, but is provided with a different means of attachment to the casting Q, 85 by which all bolts and such like devices are dispensed with. A barrel-like projection, P', having an internal lug, p', is formed upon said shoe, and receives a cylindrical projection, Q', 90 on the casting Q, which has a groove, q', therein, into which the projection p' fits. When these two parts are placed together, (as will be presently described,) they are held from coming apart by this arrangement. A portion, P'', 95 having a concave surface on which is a rib, p'', is also formed on the shoe P on the opposite side of the casting Q from the projection P'. A groove, q'', in the corresponding face of the casting Q fits over this rib p'', and aids in holding the parts in proper relative position. A handle, P', is bolted fast to the shoe, whereby the point of the shoe may be elevated or depressed. It has a stem, p', which engages with the casting Q, and thus said handle is made to 105 serve also as a brace between the parts P and Q, as hereinafter specified.

The casting Q connects the gear-case C and the shoe P together, and forms bearings for the shaft M and the inner end of the cutter-bar N. 110 It is attached to the gear-case C by being screwed into a projecting portion, e, formed thereon to receive it, and to the shoe P by the cylindrical projection Q', which enters the cylindrical opening in the projection P' on said shoe. It is held from displacement when in position by the grooves q' and q'' and the lugs or ribs p' and p'', which engage therewith. The parts P and Q are connected together by being placed in position substantially at right angles 115 to each other, (see Fig. 4,) in which position the lugs, ribs, and grooves are in such relation that the casting Q may be slipped on the shoe P until the engaging portions are in proper 120 relation. The parts are then turned until they 125 occupy the relation to each other shown by the other figures, when the lugs, ribs, and grooves interlock, and the casting and shoe are thus held together without the use of any bolts or other 130 separate fastening devices, and the cost of such devices and the fitting incident to the use of the same is thus saved. The casting Q has upon its side a segmental slide, q'', with which the brace end p' of a combined brace and han-

dle, P^3 , on the shoe P engages. As said handle is moved back and forth in elevating or depressing the shoe, said brace end moves in said slide, but bears uniformly thereon at all times. By this means a brace is secured between the shoe P and casting Q without in any way interfering with the usual independent movement of said parts.

The brace R extends from the bearing B' on the axle B to an eye, r , on the casting Q , and prevents said casting, the shoe, and cutting mechanism from being forced or pulled around by the resistance of the cutting pressure, while at the same time it permits the cutter and finger bars to be freely lifted or otherwise operated in the usual manner.

The brace S extends from the bearing B' to past the tongue D . It holds said tongue from being twisted around, and supports the wheel 20 of the cutter-bar-lifting mechanism T . It is only peculiar in extending out to a point nearly directly above the heel of the cutter-bar, and thus supporting the lifter in a position where it can be the most effective, which, as there is 25 no frame-work of the ordinary character on this machine, would otherwise be impracticable.

The cutter-bar lifter is or may be of any of the varieties which have been described in previous applications for Letters Patent which I have made, or such other as may hereafter be adopted, a cutter-bar lifter forming no part of my present invention.

The machine as a whole, it will be observed, 35 has but few bolts or nuts, but is fastened together mainly by means of the parts fitting together and interlocking with each other. This, together with the addition of a fly-wheel to the mechanism for driving the cutter-bar, 40 the lightening and strengthening of the finger-bar and cutter-bar, and the improved and inexpensive means of securing the fingers and knives thereon, form the features of my invention, and render it light, strong, and of 45 comparatively small cost.

Having thus fully described my said invention, what I claim as new, and desire to secure by Letters Patent, is—

1. The combination, with the shaft M of a 50 mowing-machine, which connects the driving-gear and the cutter-bar, said shaft having the ratchet-faced hub m rigidly mounted thereon, of the fly-wheel M' , loosely mounted on said shaft, and having the ratchet-faced hub m' ,

which is adapted to engage with the hub m , 55 the teeth of said ratchets being inclined in the direction which permits the shaft to turn without turning the fly-wheel, substantially as and for the purposes set forth.

2. The combination of the gear-case C , the 60 casting Q , and the shoe P , said casting Q being secured to said gear-case by being screwed directly into a portion of said gear-case and to said shoe by having a portion, Q' , thereof inserted in a suitable opening in a projection, 65 P' , thereon, said parts being secured together by the formation thereof, substantially as set forth.

3. The combination of the casting Q and the shoe P , said casting being provided with the 70 projection Q' , having a groove, and said shoe having a projection, P' , through which is an opening, in which is a suitable lug to engage with said groove, substantially as set forth.

4. The combination of the shoe P , having 75 projection P' and portion P^2 , and casting Q , having projecting portion Q' , and a face fitting the portion P^2 , said face and said portion being provided, respectively, with the groove q^2 and the rib p^2 , substantially as shown and 80 specified.

5. The combination of the casting Q and the shoe P , said casting having a segmental slide, q^3 , and said shoe having a combined lever and brace, P^3 , on which is a stem, p^3 , which engages 85 with said segmental slide, substantially as shown and specified.

6. The combination, in a mowing-machine, with the axle, tongue, and cutter-bar lifter, of the brace S , secured to said axle at one end 90 by a bearing, B' , located between collars $b' b'$, and to said tongue near the other end, and extending across said tongue and supporting said cutter-bar lifter upon its projecting end, substantially as shown and specified. 95

7. The combination, in a mowing-machine, of the axle B , wheel A , spokes a , turned out at the lower end where they enter the hub, the ratchet-wheels A^2 , the pawls a' , and springs a^2 , substantially as described, and for the purposes specified. 100

In witness whereof I have hereunto set my hand and seal, at Indianapolis, Indiana, this 28th day of November, A. D. 1882.

HORACE R. ALLEN. [L. S.]

In presence of—

C. BRADFORD,
E. W. BRADFORD.
